[57] CLAIM

The ornamental design for an umbrella scabbard, substantially as shown and described.

DESCRIPTION

FIG. 1 is a front elevational view of an umbrella scabbard showing my new design;

FIG. 2 is a rear elevational view thereof;

FIG. 3 is a left side elevational view thereof showing centrally disposed tie tapes in alternate position relative to that seen in FIG. 2.

FIG. 4 is a top plan view thereof;

FIG. 5 is a bottom plan view thereof;

FIG. 6 is a fragmentary cross-sectional view taken along line 6—6 of FIG. 3.

FIG. 3
